(57) **CLAIM**

The ornamental design for a floating platform, as shown and described.

DESCRIPTION

FIG. 1 is a top perspective view of a platform for yachts; FIG. 2 is a bottom perspective view thereof; FIG. 3 is a left and right side view thereof; FIG. 4 is a front and rear view thereof; FIG. 5 is top view thereof; and, FIG. 6 is a bottom view thereof.

The shading lines shown in the drawing represent the three-dimensional contour of the claimed design, and are not intended to indicate surface decoration.

Shading lines are for illustrative purposes only and form no part of the claimed design.

1 Claim, 6 Drawing Sheets
